[57] **CLAIM**

The ornamental design for a face panel of automobile acoustic amplifier including transparent cover with twin wattage meters, as shown and described.

DESCRIPTION

FIG. 1 is a plan view of a face panel of automobile acoustic amplifier including transparent cover with twin wattage meter showing my new design;

FIG. 2 is a right side view thereof, the left side view being a mirror image;

FIG. 3 is an end view thereof, the opposite end being a mirror image;

FIG. 4 is a plan view of a second embodiment of FIG. 1; FIG. 5 is a right side view thereof, the left side view being a mirror image;

FIG. 6 is an end view thereof, the opposite end being a mirror image;

FIG. 7 is a plan view of a third embodiment of FIG. 1; FIG. 8 is a right side view thereof, the left side view being a mirror image; and,

FIG. 9 is an end view thereof, the opposite end being a mirror image.

The broken line showing on FIGS. 1—9 is for illustrative purposes only and forms no part of the claimed design.
